DESIGN FOR A HANDLE FOR KITCHEN
UTENSILS OR SIMILAR ARTICLES

Joseph Orton Gadd, Wallingford, Conn., assignor to R. Wallace & Sons Manufacturing Company, Wallingford, Conn., a corporation

Application March 8, 1933. Serial No. 47,417

Term of patent 7 years

To all whom it may concern:

Be it known that I, JOSEPH ORTON GADD, a citizen of the United States, residing at Wallingford, in the county of New Haven and State of Connecticut, have invented a new, original, and ornamental Design for a Handle for Kitchen Utensils or Similar Articles, of which the following is a specification, reference being had to the accompanying drawing, forming part thereof.

Fig. 1 is a side view of a handle for kitchen utensils or similar articles showing my new design;

Fig. 2 is a plan view of the same;

Fig. 3 is a sectional view on the line 3—3 of Fig. 1; and

Fig. 4 is a top perspective view.

The dominant characteristic of applicant's design resides in a handle of polygonal form having facets at one end and grooves or flutes extending lengthwise of the handle and merging into the facets and exhibiting a panel effect.

I claim:

The ornamental design for a handle for kitchen utensils or similar articles as shown and described.

JOSEPH O. GADD.
